UNITED STATES PATENT OFFICE.

HERBERT E. BANDTEL, OF MILWAUKEE, WISCONSIN, ASSIGNOR OF ONE-HALF TO
ROBERT H. BECKER, OF MILWAUKEE, WISCONSIN.

BAR TIE AND SUPPORT.

1,144,093.

Specification of Letters Patent. Patented June 22, 1915.

Application filed April 22, 1914. Serial No. 833,634.

To all whom it may concern:

Be it known that I, HERBERT E. BANDTEL, a citizen of the United States, and resident of Milwaukee, in the county of Milwaukee, 5 and State of Wisconsin, have invented new and useful Improvements in Bar Ties and Supports, of which the following is a description, reference being had to the accompanying drawings, which are a part of this 10 specification.

This invention has for its object to provide a spring clip as a means for tying together the cross rods of reinforcements in concrete building operations.

15 An object of the invention is to dispense with the necessity for manipulation, such as the tying of wire at the intersection of the cross rods, or the bending of sheet metal clips in order to fasten the cross rods together.

20 Another object in view is the desirability of utilizing such a spring metal clip for holding the reinforcing rods above the floor of the form in which the concrete is to be 25 poured, while at the same time entirely embedding the clips in the concrete by arching their bases to permit the concrete filling in therebetween.

25 A still further object is to give to such a 30 bar tying and supporting clip a rounded bearing surface which will prevent its being forced by the weight of the metal reinforcement into the false work so as to project from the surface of the work when the false 35 work is removed.

With the above and other objects in view the invention consists in the bar tie and support as herein claimed and all equivalents.

40 Referring to the accompanying drawings in which like characters of reference indicate the same parts in the different views: Figure 1 is a perspective view of a bar tie and support constructed in accordance with 45 this invention, the crossed reinforcing rods being shown in dotted lines; Fig. 2 is an end view thereof with the reinforcing rods in full lines; and, Fig. 3 is a side view thereof.

50 In these drawings 10 indicates the arched base of the sheet metal spring clip forming the bar tie and support of this invention, the arched base having rounded edges 11 on which it bears on the floor of the mold 55 not shown. The single strip of sheet metal

constituting the clip continues at each side of the arched base 10 upwardly and inwardly to form converging cheek portions 12 which are split centrally from the top so as to be divided into pairs of spring fingers, the spring fingers of each pair converging with the spring fingers of the other pair. At their upper ends the spring fingers 12 are turned outwardly to produce a flaring throatway between them, and the resiliency 60 of the spring fingers permits them to yield to the admission of reinforcing rods 13 when pressed between them after having placed reinforcing rods 14 within the slots which divide the side cheeks of the clip into the 65 spring fingers. The slots do not extend to the rounded edges 11 of the base, but terminate at a distance above the rounded bearing surfaces of the base greater than the distance of the arched portion of the base above said 70 bearing surfaces, so that the reinforcing bar 14 rests on the upstanding edges of the side cheeks within the slots thereof and is spaced above the floor of the mold a sufficient distance to permit the concrete to flow 75 beneath it to give the proper fireproof protection and to embed the sheet metal clip without leaving any portion thereof protruding from the finished work.

The converging spring fingers serve to 80 hold the reinforcing shrinkage rods 13 firmly against the larger tension bars 14 when they are forced into place. The assembling of the reinforcing rods with the use of the spring clips of this invention is 85 a very simple matter, merely requiring the rods to be placed in their proper positions in the clips where the clips will hold them without the necessity for a bending of parts, but merely relying upon the spring action 90 of the clip to yield to the forcing of the parts into their proper place and to retain them in position when so placed.

The slots in the side cheeks of the clip have square ends so that the reinforcement 100 bars 14, which are square in cross section, may fit therein, and the cross rod 13 is also shown as square in cross section, but it is obvious that this shape of the parts may be departed from within the scope of the invention.

What I claim as new and desire to secure by Letters Patent is:

1. A bar tie and support for crossed reinforcing rods, comprising a strip of sheet 110

metal bent to form an arched base with rounded edges and continuing upwardly from the bearing edges to form converging side checks, said side checks being slotted from their upper edge downwardly to divide them into pairs of spring fingers, the slots between the fingers being adapted to receive one of the reinforcing rods and the pairs of spring fingers being adapted to receive another reinforcing rod of greater thickness than the distance between the spring fingers so that said rod is held thereby with spring pressure, the upper end of the spring fingers being turned outwardly to facilitate the passing of the last mentioned reinforcing rod therebetween.

2. A bar tie and support for crossed reinforcing rods, comprising a single strip of sheet metal bent to the shape of the letter W with an arched base having rounded bearing edges with converging side cheeks extending upwardly therefrom, said side cheeks being slotted from their upper edges downwardly to a point above the bearing surfaces higher than the arched portion of the base, the slots being square at their ends and adapted to receive a square reinforcing bar passing through the slots of both cheek members, said slots dividing the cheek members into pairs of spring fingers converging and then diverging to produce contracted throatways between them to receive another reinforcing rod of greater thickness than the distance between the contracted portion of the spring fingers and to retain said rod in place by their spring pressure therein.

In testimony whereof, I affix my signature, in presence of two witnesses.

HERBERT E. BANDTEL.
